US0D1057880S

(12) **United States Design Patent** (10) Patent No.: **US D1,057,880 S**
(45) Date of Patent: ** Jan. 14, 2025

(54) PISTOL	2,464,010 A	3/1949	Vonella
(71) Applicant: HS Produkt D.O.O. , Karlovac (HR)	2,489,816 A	11/1949	Reilly
(72) Inventors: Dubravko Trpčić , Karlovac (HR); Stephen H. McKelvain , Geneseo, IL (US); Dennis J. Reese , Geneseo, IL (US); Charles David Williams , Geneseo, IL (US)	2,943,412 A	7/1960	Mcnally
	3,207,037 A	9/1965	Pachmayr
	3,411,408 A	11/1968	Pachmayr et al.
	3,564,967 A	2/1971	La Violette et al.
	3,745,881 A	7/1973	Roy
	4,222,308 A	9/1980	Arnett
	4,463,655 A	8/1984	Krieger
	4,575,963 A	3/1986	Ruger et al.
	D292,112 S	9/1987	Ruger et al.
	4,707,942 A	11/1987	Peters
	D293,357 S	12/1987	Ruger et al.
	4,907,489 A	3/1990	Teague
	4,916,843 A	4/1990	Beretta
	4,996,787 A	3/1991	Holcomb et al.
	D316,587 S	4/1991	Sanford
	5,024,016 A	6/1991	Smith
	5,042,185 A	8/1991	Justice, Sr.
	5,267,407 A	12/1993	Bornancini
	D345,002 S	3/1994	Strayer et al.
	D346,196 S	4/1994	Ruger
	D359,098 S	6/1995	Stevens
	5,433,134 A	7/1995	Leiter
	D365,103 S	12/1995	Iacobellis
	5,585,589 A	12/1996	Leiter
	5,741,996 A	4/1998	Ruger et al.
	5,753,848 A	5/1998	Kart
	5,969,285 A	10/1999	Krebs
	D416,013 S	* 11/1999	Muraki .....
	D444,786 S	7/2001	Otomi et al.
	6,283,006 B1	9/2001	Szabo et al.
	6,298,594 B1	10/2001	Strayer
	6,318,231 B1	11/2001	Kart
	6,374,526 B1	4/2002	Mochak

CLAIM

The ornamental design for a pistol as shown and described.

DESCRIPTION

FIG. 1 is a left view of the pistol showing my new design;
FIG. 2 is a right view thereof;
FIG. 3 is a front view thereof;
FIG. 4 is a back view thereof;
FIG. 5 is a top view thereof;
FIG. 6 is a bottom view thereof; and,
FIG. 7 is a perspective view thereof.

The broken lines in the drawings depict unclaimed portions of the pistol only and form no part of the claimed design.
